(57) **CLAIM**

The ornamental design for an animal training transmitter, as shown and described.

DESCRIPTION

FIG. 1 is a perspective view of an animal training transmitter showing the new design;

FIG. 2 is a top view of the animal training transmitter of FIG. 1;

FIG. 3 is a right view of the animal training transmitter of FIG. 1;

FIG. 4 is a front view of the animal training transmitter of FIG. 1;

FIG. 5 is a left view of the animal training transmitter of FIG. 1;

FIG. 6 is a back view of the animal training transmitter of FIG. 1;

FIG. 7 is a bottom view of the animal training transmitter of FIG. 1;

FIG. 8 is a perspective view of the animal training transmitter from another direction than FIG. 1;

FIG. 9 is a top view which shows that the lower hook part of this design is formed in a carabiner type, with the lower hook part being opened; and,

FIG. 10 is a bottom view which shows that the lower hook part of this design is formed in a carabiner type, with the lower hook part being opened.
